United States Patent Office.

W. T. MUNGER, OF BRANFORD, ASSIGNOR TO P. CORBIN AND F. CORBIN,
OF NEW BRITAIN, CONNECTICUT.

Letters Patent No. 81,981, dated September 8, 1868.

IMPROVEMENT IN REVERSIBLE LATCHES.

The Schedule referred to in these Letters Patent and making part of the same.

TO ALL WHOM IT MAY CONCERN:

Be it known that I, W. T. MUNGER, of Branford, in the county of New Haven, and State of Connecticut, have invented, made, and applied to use, a certain new and useful Improvement in Locks; and I do hereby declare the following to be a full, clear, and exact description of the said invention, reference being had to the annexed drawing, making part of this specification, wherein—

Figure 1 is an elevation of said lock, with the cap-plate removed, the parts being in the usual position for use, and

Figure 2 is a similar view of the lock, with the parts in the position they assume when the latch can be turned for reversing the bevel to suit right or left-hand doors.

Similar marks of reference denote the same parts.

The object of this invention is to allow for reversing the latch without disconnecting any of the parts from the lock; and said invention consists in a divided horse-shoe slide, the parts being hinged together, so that the horse-shoe can be opened and moved forward sufficiently to allow the square end of the latch to be revolved to reverse the bevel at the end, and when the latch is pressed back into the lock, and the hub of the spindle partially turned, the cam thereof latches past the swinging portion of the horse-shoe, and the lock is ready for use.

In the drawing, *a* represents the lock-case; *b*, the bolt, with its tumbler as usual. My latch, however, may be used in a case without a bolt. *c* is the hub of the spindle, with the cams 2, 2; *d* is one portion of the horse-shoe, extending to the arm or block 3, into which the end of the shank *f* of the latch *g* is entered and riveted, or otherwise secured, so that it may be revolved in said block 3, but the shank, latch, and portion *d* of the horse-shoe, all slide back and forth together when acted upon by the cam 2, or by the latch-spring *h*.

i is the other portion of the horse-shoe, united to the part *d* by the pivot *k*, and *l* is a spring, tending to press the hooks 4 of the horse-shoe towards each other.

An opening is provided in the cap-plate of the lock, as shown by red lines, so that a screw-driver or other instrument may be inserted, to act upon the portion 5 of the horse-shoe, *i*, and disconnect its hook 4 from the cam 2, and thereby the spring *h* will be at liberty to project the latch, or it can be drawn forward sufficiently to clear the square base of the latch from the mortise in the face of the lock, and thereby said latch is free to be turned to place its bevelled end on the proper side for the door to which it is to be applied. The latch is then pushed into the lock and the hub *c* turned, so that its cam presses back the part *i* of the horse-shoe, and the hook 4 springs back to its place.

What I claim, and desire to secure by Letters Patent, is—

The divided horse-shoe, formed of the part *i*, pivoted to the portion *d*, in combination with the latch *g* and shank *f*, attached to the horse-shoe, so that it may be revolved for reversing said latch, substantially as set forth.

In witness whereof, I have hereunto set my signature, this twenty-first day of March, 1868.

W. T. MUNGER.
